DESIGN FOR A MICROPHONE SUPPORT

Sidney N. Shure, Chicago, Ill., assignor to Shure Brothers, a partnership composed of S. N. Shure and Arnold I. Shure

Application December 9, 1935, Serial No. 59,981

Term of patent 7 years

To all whom it may concern:

Be it known that I, Sidney N. Shure, a citizen of the United States of America, residing in Chicago, in the county of Cook and State of Illinois, have invented a new, original, and ornamental Design for a Microphone Support, of which the following is a specification, reference being had to the accompanying drawing, forming a part thereof, in which

I claim:

The ornamental design for a microphone support substantially as shown.

SIDNEY N. SHURE.
